US0D1047909S

(12) **United States Design Patent** (10) **Patent No.:** **US D1,047,909 S**
(45) **Date of Patent:** **** Oct. 22, 2024**

(54) **ENERGY STORAGE POWER SUPPLY**

(71) Applicant: **Shenzhen Ampower New Energy Co., Ltd.**, Shenzhen (CN)

(72) Inventors: **Xiaofeng Liu**, Shenzhen (CN); **Heping Chen**, Shenzhen (CN); **Jiuzhi Lai**, Shenzhen (CN); **Xingqun Liao**, Shenzhen (CN); **Dangyu Pan**, Shenzhen (CN)

(**) Term: **15 Years**

(21) Appl. No.: **35/519,367**

(22) Filed: **Nov. 30, 2023**

(80) **Hague Agreement Data**

Int. Filing Date: **Nov. 30, 2023**

Int. Reg. No.: **DM/233614**

Int. Reg. Date: **Nov. 30, 2023**

Int. Reg. Pub. Date: **Dec. 15, 2023**

Primary Examiner — Rosemary K Tarcza

(57) **CLAIM**

The ornamental design for energy storage power supply as shown and described.

DESCRIPTION

The patent or application file contains at least one drawing executed in color. Copies of this patent or patent application publication with color drawing(s) will be provided by the Office upon request and payment of the necessary fee.

1.1 : Perspective

1.2 : Front

1.3 : Back

1.4 : Left

1.5 : Right

1.6 : Top

1.7 : Bottom

1.8 : Perspective

Use of this product design: This design product is used for energy storage and power supply; Design essentials of this product design: The shape; Picture or image that best illustrates the design essentials: Perspective view **1.1**.

The portion of the design shown in the color blue is for the purpose of illustrating environmental structure and forms no part of the claimed design.

1 Claim, 8 Drawing Sheets
